LINK ROD AND METHOD OF MAKING
SAMEGeorge H. Hufferd, Detroit, Mich., assignor to
Thompson Products, Incorporated, Cleveland,
Ohio, a corporation of Ohio

Application November 7, 1938, Serial No. 239,230

8 Claims. (Cl. 29—152)

This invention relates to connection members adapted to receive inserts therein and having integral portions for tightening the connecting member around an insert. The invention also includes a process of making such connection members from strips of metal.

More specifically, this invention relates to link rods, such as tie rods or the like, which are provided with integral clamping ears for contracting the rod around an insert. The invention specifically includes a process of making such link rods from flat strip steel stock by stamping and bending operations.

While the invention will be hereinafter specifically described in connection with tie rods, it should be understood that the principles of the invention are not limited to such use and that the process and product of the invention relate to the provision of connection members in general.

20 Tie rods have heretofore been prepared from seamless or butt-seam tubing. The ends of the rods have been internally threaded and longitudinally slotted. Separate clamping rings have been disposed around the ends of the rods for tightening or contracting the rods around the shanks of tie rod joints that have been threaded into the rods. This construction is expensive, requires many mechanical operations, and involves the use of separate clamping rings not forming a direct part of the tie rods.

The present invention now provides for the manufacture of tie rods and the like connection members by simple bending and stamping operations. The members produced have integral clamping ears thereon that take the place of the heretofore necessary separate clamping rings.

According to this invention, the connection members are formed from flat metal strips by compound dies which shape the clamping ear segments along the sides of the strips, punch out holes through the clamping ears, and turn up the sides of the strips to start the bending operation. The thus formed strips can then be readily bent around a mandrel into the form of rods, with the clamping ears depending from opposite sides of the rods in spaced opposed relation.

One of the features of the invention includes the formation of inturned flanges around the peripheries of the clamping ears, which flanges merge into and are integral with the body of the link rod. The flanges prevent flexing of the ears when the same are drawn toward each other by means of a clamping bolt so that the rod itself will be contracted around an inserted member without bending the ears relative to the rod. The rod is slotted for a distance beyond the ears to facilitate contraction around an insert.

In one modification of the invention, the stamping dies cut away portions of the sides of

the strip so that the body of the resulting link rod will have a simple butt-seam.

In another modification of the invention, all of the strip stock is used along the edges and a flange is formed therefrom to provide, along the body of the resulting link rod, a pair of contiguous laterally projecting reinforcing flange portions.

It is, then, an object of this invention to provide a connection member having integral dependent ears for contracting the member about an insert.

A further object of the invention is to form from flat metal strip stock a connection member having integral clamping ears.

A further object of the invention is to provide a connection member or link rod having integral spaced opposed ear portions with inturned integral flanges therearound to resist flexing of the ears.

A further object of the invention is to provide connection members or link rods from flat steel strips by stamping and bending operations.

A further object of the invention is to provide a tie rod having integral opposed clamping ears stiffened by inturned flanges and separated by slots extending from each side thereof, and adapted to cooperate with a clamping bolt for decreasing the width of the slots to contract the rod.

Other and further objects of the invention will become apparent to those skilled in the art from the following detailed description of the annexed sheet of drawings, which discloses preferred embodiments of the invention.

On the drawing:

Figure 1 is a broken side elevational view of a tie rod according to this invention having the shanks of tie rod joints threaded into the ends thereof and clamped therein by means of clamping bolts inserted through integral clamping ears provided on the rod;

Figure 2 is a broken plan view showing a stamping prepared from a flat strip of steel, illustrated in dotted lines, which stamping is bent to form the rod shown in Figure 1;

Figure 3 is a cross-sectional view taken along the line III—III of Figure 2;

Figure 4 is a cross-sectional view taken along the line IV—IV of Figure 1 with parts omitted and illustrating the bolt in dotted lines;

Figure 5 is a cross sectional view taken along the line V—V of Figure 1;

Figure 6 is a cross sectional view taken along the line VI—VI of Figure 4;

Figure 7 is a broken plan view of a stamping prepared according to this invention for forming a modified type of tie rod according to this invention from a flat strip of steel shown in dotted lines;

Figure 8 is a cross sectional view taken along the line VIII—VIII of Figure 7;

5 Figure 9 is a vertical cross sectional view taken through a link rod prepared from the stamping shown in Figures 7 and 8;

10 Figure 10 is a vertical cross sectional view taken through a rod produced from the stamping shown in Figures 7 and 8 at a point along the length of the rod spaced from the clamping ears; and

15 Figure 11 is a cross sectional view taken along the line XI—XI of Figure 9.

As shown in the drawing:

20 The reference numeral 10, in Figure 1, designates a tie rod according to this invention. The tie rod 10 has open ends 11 and 12 which are internally threaded for a desired distance into the rod for receiving in threaded relation the externally threaded shanks 13 of tie rod joint housings such as 14. The joint housing 14 has a stud 15 projecting therefrom. The stud 15 is rotatable and tiltable in the housing 14.

25 The rod 10 is provided with pairs of integral clamping ears 16 and 17 near the ends 11 and 12 thereof. Each pair of ears 16 and 17 receive clamping bolts 18 and 19 respectively therethrough for contracting the threaded ends of the rod 10 around the shanks 13 to hold the shanks against rotation relative to the tie rod.

30 According to this invention, the tie rod 10 is formed from a flat strip of metal designated by the reference numeral 20 in Figure 2. A stamping 21 is formed from the flat strip 20 by compound trimming, forming, and punching dies (not shown). The sheet 20 is first trimmed, as shown in dotted lines, along the sides thereof to define projecting ear segments 16a and 16b near one end of the strip and similar projecting ear segments 17a and 17b near the other end of the strip. The central portion of the trimmed strip is wider than the portions adjacent the ear segments, so that the edges 26 thereof project beyond the edges adjacent the ear segments, as shown in dotted lines. The segments 16a and 16b are transversely aligned on opposite side edges of the strip. Likewise, the ear segments 17a and 17b are transversely aligned on opposite side edges of the strip.

35 The strip 20 is punched to form a hole 22 through ear segment 16a, 16b, 17a and 17b.

40 The forming dies (not shown) turn up flanges 23 around the outer edges of the ear segments 16a, 16b, 17a and 17b and simultaneously turn up the body portion of the strip along the marginal sides thereof to form rounded portions 24 between the ear segments and also at the ends of the strip, as shown in Figures 2 and 3.

45 During this bending operation, the forming die (not shown) holds back the ear segments to define flat pockets 25 therein. These pockets 25, as best shown in Figure 2, extend inwardly from the projecting portion of the ear segments so that in the final link rod these pockets will be in full communication with the interior of the rod.

50 As best shown in Figure 3, the turned-up portions 24 of the stamping 21 are arcuate in shape and merge into and are integral with the flanges 23 formed around the projecting ear segments so that the pockets 25 are bordered by continuous walls along the sides of the stamping.

55 The stamping 21 is next bent around a cylindrical mandrel to bring the projecting edges 26 of the turned-up portions 24 into contiguous relation, as shown in Figures 4, 5 and 6. A butt-seam is thus formed. However, since the edges

60 of the trimmed strip prior to bending extend beyond the edges of the strip adjacent the ear segments, the placing of these edges 26 into contiguous relation will leave gaps or slots 27 between the ears and extending for a distance on each side of the ears.

65 Thus, as best shown in Figures 4 and 6, the ear segments 16a and 16b with their inturned flanges 23 are in spaced opposed relation, and the slot 27 extends beyond the ears on both sides. The slot 27 preferably extends to the adjacent end of the rod, as shown in Figure 6.

70 When a bolt such as the bolt 18 is inserted through holes 22 of the ears and the nut 19b is tightened on the bolt, the ears can be drawn together to decrease the width of the slot 27 and thus contract the diameter of the rod 10 at least for a distance along the length of the rod.

75 The ears are stiffened or reinforced by the inturned flanges 23, and since these flanges are integral with and merge into the body of the rod 10, the ears will not flex or bend during the clamping operation.

80 The rod 10 can be internally threaded as shown at 28 in Figure 4 for receiving an externally threaded shank such as 13, shown in Figure 1.

85 From the above description of Figures 1 to 6, it should be understood that the rod 10 is formed from a flat strip of metal by trimming, punching, stamping, and bending operations. The trimming, punching and stamping operations can be performed by compound dies in a single step. The bending operation of the stamping thus produced is readily performed around a shaping mandrel.

90 The link rod thus formed has great strength, and the integral ears are rigidly reinforced against bending relative to the body of the rod.

95 In the modification shown in Figures 7 to 10, inclusive, a trimming operation to remove portions of the initial flat metal strip is not used, and all of the metal of the original strip, except that punched out to form the holes through the ears, is present in the final link rod.

100 As shown in Figure 7, a flat strip of metal 30 is punched and stamped to form a stamping 31. The stamping 31 is formed by punching holes 32 through the strip 30 at points where the clamping ears are to be formed. Dies (not shown) 50 then hold the punched strip to form pockets 33 surrounding the holes 32, while the edges of the strip are turned upwardly to form flanges 34 around the pockets 33. At the same time the side portions of the strip are turned upwardly to 55 form curved side portions 35. The portions 35 are so curved as to start the forming of a tubular rod and are spaced inwardly from the marginal edges of the strip 30 so that flange portions 36 extend outwardly therefrom at levels some 60 what above the flanges 34. These flange portions 36, however, merge into and are integral with the flanges 34.

105 The flange portions 34 extend for a distance on each side of the pockets and preferably to the adjacent ends of the strip so that the higher flanges 36 are only along the intermediate portion of the strip in spaced relation from the pockets 33. Curved side wall portions 36a connect the higher flanges 36 with the flanges 34. Likewise, 70 side walls 33a connect the bottoms of the pockets 33 with the flanges 34.

110 The stamping 31 thus formed its next bent around a cylindrical mandrel to form the rod 40 shown in Figures 9, 10 and 11. As best shown 75

in Figure 9, the pockets 33 are bordered by the side walls 33a, which merge with the flanges 34. The flanges 34, in turn, merge into the flanges 36, being connected by the walls 36a.

5 Spaced opposed ears 37 are thus formed. These ears have aligned apertures 32 therethrough and can receive a clamping bolt such as 18, shown in Figure 4, to draw the flanges 34 toward each other for narrowing slots 39 formed between these 10 flanges.

10 The rod 40 will thus have depended flanges 36 along the length thereof, which flanges are bowed outwardly and merge with the flanges 34 that border the ears 37 and are connected to the 15 ears through the side walls 33a. These side walls are actually inturned flanges reinforcing the ears against flexing. The ears 37 are thus stiffened and reinforced by the integral bordering side walls 33a, the flanges 34, and the contiguous 20 flanges 36. The ears will not flex or bend relative to the rod 40 and will serve to decrease the diameter of the rod for clamping the same around a threaded insert. The interior of the rod 40 can be threaded for a distance from the ends 25 thereof to receive in threaded relation thereto shanks such as 13 described in Figure 1.

It should be appreciated that the stamping technique can be widely varied without departing from the principles of this invention. The invention in its broader aspect includes the formation of connection members from strip stock by stamping and bending operations which provide integral clamping ears on the member.

I claim as my invention:

35 1. A tie rod comprising a hollow tube having internally threaded ends, spaced opposed integral clamping ears near each of said ends depending laterally from the tube, inturned flanges re-enforcing said ears against flexing and defining a slot therebetween and said ears being apertured 40 for receiving a clamping member therethrough to draw the ears together for decreasing the size of the rod at points adjacent said ears.

2. The method of making a connection member 45 adapted to be contracted around an insert which comprises providing a flat strip of metal, bending into an arcuate shape a portion along each side of the strip spaced inwardly from the side edges of the strip while holding aligned localized portions flat to thereby define aligned 50 pockets bounded by side walls merging into flat flanges extending from the arcuately bent portions of the strip to the strip edges, bending aligned portions of such flat flanges to a higher 55 level at a point spaced from the side walls, and bending the thus formed blank into rod form with the aligned flange portions in contiguous relation, the remainder of the flat flanges in spaced opposed relation, and the localized portions defining spaced opposed ears reinforced by the side walls.

3. A connection link having a slotted portion 60 adapted to be contracted around an insert which comprises a hollow one-piece tube, spaced opposed integral apertured clamping ears depending laterally from the tube, said ears having side walls reinforcing the ears against flexing, and said tube having a slot between said ears whereby a bolt and nut assembly is adapted to be extended through said apertured ears to draw the 65 ears toward each other for decreasing the size of the tube at points adjacent said ears.

4. A sheet metal link rod having a slotted portion adapted to be contracted around an insert which comprises a hollow one-piece sheet metal tube having an internally threaded slotted end portion, spaced opposed integral clamping ears 5 depending laterally from the threaded end portion of the tube on each side of the slot therein, inturned flanges reinforcing said ears against flexing, said ears being apertured for receiving a clamping member therethrough to draw the 10 ears together for narrowing the slot and decreasing the size of the tube whereby an insert threaded into the threaded end of the tube will be locked therein.

5. The method of making a sheet metal rod 15 member adapted to be contracted around an insert which comprises stamping a portion along each side of a strip of metal while holding localized opposed portions flat to define aligned pockets bounded by upturned side walls, and 20 bending the thus formed blank into rod shape with the pockets depending from the rod in spaced opposed relation and with a slot between the pockets.

6. The method of making a connection link rod 25 having integral laterally depending ears adapted to cooperate with a nut and bolt assembly for tightening the rod about an inserted member which comprises stamping a strip of metal to form transversely aligned pockets in opposite 30 sides thereof defined by upstanding flanges around the outer periphery of the pockets, stamping upturned side portions along the length of the strip on each side thereof merging into and integral with the inner ends of the flanges but 35 extending above the flanges, and bending the thus formed blank into rod shape to bring the upturned portions together while at the same time bringing the flanges into spaced opposed relation whereby the pockets form dependent aligned 40 flanged ears on each side of a slot.

7. The method of making a connection link 45 adapted to be contracted around an insert which comprises trimming a sheet of metal to form aligned ear segments on opposite sides thereof and aligned projecting side edges in spaced longitudinal relation from the ear segments, turning up flanges around the ear segments, bending the sides of the strip into curved shape while holding the ear segments flat, and bending the thus 50 formed blank around a mandrel to bring together the projecting side edges thereof to produce a butt-seamed tube with a localized longitudinally slotted portion and a flanged laterally depending integral ear on each side of the slot.

8. A connection link rod adapted to be contracted around an insert comprising a sheet metal tube having dependent abutting flanges extending laterally therefrom along the length thereof and bowed outwardly along a localized portion 60 thereof to define a slot therebetween, and a laterally depending flanged ear integral with each flange intermediate the ends of localized bowed-out portions thereof, said ears being aligned on opposite sides of the slot and having apertures 65 therethrough adapted for receiving a nut and bolt assembly to draw the ears together for decreasing the size of the slot to contract the tube around an insert.

GEORGE H. HUFFERD. 70
